UNITED STATES PATENT OFFICE

ROSCOE C. IDDINGS, OF DAYTON, OHIO, ASSIGNOR TO THE FYR-FYTER COMPANY, OF DAYTON, OHIO, A CORPORATION OF OHIO

FIRE EXTINGUISHER

Application filed March 3, 1924. Serial No. 696,429.

This invention relates to fire extinguishers of the small portable type from which fire extinguishing liquid is ejected by means of a hand operated pump. Fire extinguishers of this type are provided with a nozzle fixed with reference to the liquid container, which container constitutes the body of the fire extinguisher, and it is therefore necessary to hold the container in such a position that the stream from the nozzle will play upon the fire. Obviously, this necessitates holding the container in any of a great number of positions, and as the liquid in the container flows to the lowermost part thereof, provision must be made for carrying liquid to the nozzle, whatever the position of the latter may be.

Various devices have been produced whereby to automatically connect the nozzle with the lowermost part of the container, which devices have been more or less successful and many thousands of such fire extinguishers have been sold and are now in use. But as fire extinguishers stand for long periods of time without being used, and since devices of the kind mentioned contain gravity operated mechanism, valves, etc., which because of corrosion or even from mere disuse may be found inefficient, if not positively inoperative, when the fire extinguisher is needed, any means whereby such mechanism can be eliminated is a desideratum, provided that by such means the same, or practically the same, useful results be obtained. Moreover, as such mechanism is expensive to construct, the cost of such fire extinguishers tends to restrict the number put into use, which is another reason for a device without such mechanism being desirable.

One of the objects of my present invention is to produce a fire extinguisher which fulfills the requirements mentioned, but without gravity actuated mechanism. This is accomplished by providing a stationary

discharge tube, one end of which is connected to the nozzle, with the other or open end situated in a certain remote portion of the container. The nozzle is so situated with reference to this certain portion of the container, that the stream from the nozzle may be directed on a fire, whether it be almost overhead, almost under foot or anywhere intermediate of these extremes, while keeping lowermost the portion of the container in which the open end of the suction tube is situated.

Another object of my present invention is to provide a shut-off valve of improved construction whereby the nozzle may be closed, to prevent outflow or evaporation of the fire extinguishing liquid, and another is to facilitate assembling of the parts, this being done by mounting all of the parts upon a single member of the container before said member is united to other parts of the container, thus enabling all adjustments to be made with the parts in full view of the workman and in their ultimate relative positions. In the accompanying drawings illustrating my invention,

Fig. 1 is a longitudinal sectional view of the complete fire extinguisher;

Fig. 2 is a diagrammatic view, showing the relative positions of the nozzle and the liquid-intake;

Fig. 3 is a fragmental view showing the valve in the condition it is in when the fire extinguisher is in use.

Fig. 4 is an end view of my fire extinguisher with a portion of the handle broken away.

In certain respects my present valve mechanism resembles, although it is an improvement over, that shown in my application serially numbered 148,309.

Referring now to Fig. 1 it will be seen that the container 10 constitutes the body of my fire extinguisher. Preferably, this container is made in two pieces. The cylindri-

cal main portion and one end, which I shall refer to as the bottom, are made integral. The other end portion, 11, which I shall call the top, is in the form of a cup having a flange 12 to fit over the body 10. All of the mechanism of this fire extinguisher is mounted on the top, and when it is completed and adjusted the top is placed upon the body, the pump and other parts extending down into the body, or container, and the flange 12 is soldered to the body. Since the parts are sustained entirely by the top and are not attached to the body, the body and top might be threaded and screwed together.

15 Mounted on the top 11 is an air pump 13. As air pumps are well known and understood it will not be necessary to describe this pump in detail. The top 11 is provided with a hollow boss 14 into which the end of the tube that forms the cylinder of the pump is inserted and soldered. In the center of the boss 14 is a hollow superboss 15, provided with a central hole through which the piston rod 16 of the pump passes. On the outer end of the piston rod is mounted the operating handle 17. This handle has a hub 18 in which the piston rod is secured and the hub is provided with a recess 20, which, 25 when the piston is in its innermost position, surrounds the superboss 15. A pin 21 is inserted crosswise in the piston rod within this recess, and the top of the superboss 15 is provided with two recesses 22, on opposite sides of the piston rod, through which the extending ends of the pin 21 pass when the piston is pushed to its innermost position. Rotating the piston rod will then lock the rod in its innermost position. At its 30 inner end the piston rod is provided with a spring actuated plunger 23, the spring, not shown, tending to press the piston rod outward a short distance. One purpose of this plunger is to thrust the piston rod outward the moment the ends of the pin 21 register with the recesses 22. Thus when the handle is rotated for the purpose of releasing it, the operator needs to use no care to turn the handle just the proper distance. He simply 35 turns it, and when the ends of the pin register with the recesses the piston is thrust out, feeling which the operator knows that the handle is unlocked and ready to be reciprocated. The plunger 23 also serves as a valve 40 to seal the end of the pump cylinder, supplementing the regular spring actuated check valve, not shown. The purpose of the air pump is to compress air in the container, by which the fire extinguisher liquid is ejected. I shall now describe the valve mechanism and passages through which the liquid is discharged.

45 The top 11 is made of sheet metal and the boss 14 and the superboss 15 are formed by pressing the sheet metal outward. In like

manner an inwardly extending collar 25 is formed on the top. The open end of a cylindrical valve casing 26 is secured to this boss, preferably with solder. This casing is threaded to receive a plug 27, having a head, 50 a suitable sealing gasket 28 being placed under the head. This plug has a longitudinal bore 29, about one-third of which, at its outer end, is of smaller diameter than the remainder of the bore. A plunger 30 slides 55 in this smaller portion of the bore, and it has a head 31 in the larger part of the bore, which prevents the plunger from falling out of the bore. The inner end of the plug, indicated by the numeral 32, is arranged to act as a seat for a valve. At its inner end the casing 26 carries a tube 35. This tube connects to a standpipe formed integral with the casing, the standpipe extending some distance into the hollow part of the casing, its end being finished to form the valve seat 36. From the valve casing the tube 35 extends to the other end of the container, its open end 37 being situated near the side of the container. Further mention of this end 60 of the tube will be made presently.

65 A cup-shape valve member 40 is arranged to slide in the casing. The exterior of this member is cylindrical, and being only enough smaller than the cylindrical interior of the casing to enable it to move freely therein, it resembles a piston. This member is so placed in the casing that the standpipe extends into the cup, and a cork or soft fibre disk 41 in the bottom of the cup is adapted to cooperate with the valve seat 36 and stop the flow of liquid into the casing. The outer bottom of the cup is recessed to receive and retain a cork or soft fibre ring 42, while from the center of the bottom a 70 small stud 43 extends into the bore 29 of the plug 27. Surrounding the standpipe and confined between the end of the casing and the disk 41 in the bottom of the cup is a compression spring 44, adapted to move 75 the valve member 40 to and press the cork ring 42 against the seat 32 on the end of the plug 27. Housed in the bore 29 and surrounding the stud 43 is a second compression spring, 45. The inner end of this 80 spring bears on the head of the plunger 30, but a sealing disk 46, of cork, is interposed. This disk fits the bore 29 closely and assists in preventing leakage of liquid past the plunger. When the valve member moves 85 to the seat 32 the spring 45, moved by the valve member, pushes the disk 46 and the plunger toward the small end of the bore 29. See Fig. 3. Preferably, the length of the spring 45 is such that it will not move the 90 plunger quite as far as it might go. Thus the spring is not confined and therefore it offers no opposition to the seating of the valve member. The strength of the spring 45 is such that if the plunger 30 be pushed 95

inward the spring 45 will overpower the spring 44 and push the valve member from the seat 32 to the seat 36. See Fig. 1.

For the purpose of pushing in the plunger I provide a projection 50 extending laterally from the hub 18 of the pump handle. This projection has a flat face 51 which, when the handle is locked in with the bayonet catch, holds the plunger in the position it occupies in Fig. 1. That is, it holds the valve closed. At each side the projection 50 is beveled away from the flat face 51, as at 52, so that after the handle is locked in, continued rotation of the handle brings one of these bevels 52 into engagement with the end of the plunger and cams the plunger in. The end of the plunger is rounded so as to facilitate this action. In the center of the flat there is a slight depression 53, into which the end of the plunger may drop. The slight recession of the plunger due to this is not sufficient to impair the sealing value of the valve, while, because of the spring 45 being a rather powerful one, the plunger in this depression acts as a latch and holds the handle against accidental turning.

A port 60 is placed in the inner end of the valve casing, to which a tube 61 is connected. The other end of this tube is connected to the nozzle 62, which is rigidly mounted upon the flange 12 of the container top. Referring to Fig. 2 it will be seen that the bore of the nozzle, represented by the radial line 63, lies in a radial plane more than ninety degrees removed from the radial plane, represented by the line 64, in which lies the open end 37 of the tube 35. In this figure the end 37 of the tube is indicated with a small dotted circle placed close to the wall of the container. An opening is provided in the top for filling the container with liquid, this opening being closed by a screw-plug 65.

I shall now describe the operation of my improved fire extinguisher: Grasping the container close to the handle end with one hand the operator seizes the pump handle with the other hand, unlocks the handle by rotating it approximately ninety degrees and proceeds to reciprocate the piston of the pump. Because of the nozzle being situated at the same end of the container as the pump handle, and because the nozzle throws a stream perpendicular to the axis of the container, it is most convenient for the operator to lay the side of the container against his body, a short distance above his waist. In fact that is the natural position into which to put this fire extinguisher. He naturally faces the fire, and with the container lying against his body the stream is projected straight away from him. By rolling the container he can direct the stream upward or downward. I have found that

with the container pressed to the body with one hand while the pump piston is reciprocated with the other hand, one will naturally hold the handle end of the container at a higher level than the other end of the container. Moreover, I have found that this tendency is considerably affected by locating the pump near one side of the container. If the container be held so that the side in which the pump is located is lowermost, the operator will unconsciously give the container more inclination than he will if the pump is near the upper part of the container. This is due to one's natural tendency to assume the most effective position for putting forth a given muscular effort. In reciprocating the piston of the pump the operator will naturally hold the container at an angle which will bring the piston into alignment with his fore arm, and there is a place on his body, above his waist, against which he will naturally press the container in order to best apply the necessary force for operating the pump. In view of these facts I have located the nozzle in such a position that with the container held in the left hand and the pump operated with the right, pointing the nozzle away from the operator brings the pump side of the container underneath. And it is in this side of the container that the inlet 37 of the tube 35 is located. Referring to Fig. 2 it will be seen, keeping in mind the lower end of the container will be held several inches lower than the handle end, that by simply rolling the container the operator can direct the stream overhead, or almost under foot without raising the inlet 37 more than slightly above the lowermost part of the container. Therefore, substantially all of the liquid in the container can be thrown on a fire, regardless of the direction in which the stream must be directed.

Theoretically the nozzle should be located ninety degrees around from the radial plane in which the inlet lies. But practically this is not so. While it might be necessary, and even practicable, to stand directly under a fire, one would hardly stand directly over a fire he was fighting. For this reason I locate the nozzle more than ninety degrees, may be as many as one hundred and twenty, around from the inlet, thus reducing the distance that the inlet 37 may have to be raised above the lowermost part of the container. In practice I have found that having the stream leave the container in a line perpendicular to the longitudinal axis of the container is satisfactory, but to enable the stream to be directed vertically upward while holding the lower end of the container at a lower level than the handle end, the nozzle may be bored so that the stream inclines slightly upward with reference to the longitudi-

nal axis of the container; say ten or fifteen degrees above the perpendicular.

With the nozzle located as shown, if the operator were to hold the container with his right hand and pump with his left, the inlet 37 would be raised somewhat from the lowermost part of the container. While it is possible that some persons might make this mistake, the number is probably so small that this possibility may be ignored. Few would do it unless they were left handed, and as left handed persons are very much in the minority they may be dismissed. Moreover, it would only affect the operation of the device after the liquid was nearly exhausted. Finally, the danger of this happening may to a very large extent be eliminated by instructions printed on the container. On the other hand, the reliability of my improved device, due to its extreme simplicity and freedom from mechanism whose efficiency may be impaired through disuse or by deterioration, far offsets any possible failure of the device because of ignorance of the operator. For all fire extinguishers are subject to failure, more or less complete, because of ignorance or timidity on the part of the operator.

One of the advantages of my improved valve mechanism is that when the valve is open leakage of liquid past the plunger to the exterior of the container is prevented by what may be called the secondary valve, namely, the valve member 40 pressed against the end of the plug 27 by the spring 44. Thus a more effective seal is provided than a packing gland, while the friction of the packing gland is eliminated. Another advantage of my present valve construction resides in the stream of liquid which flows into the valve casing, being received in the cup of the valve member. This directs the liquid back toward the port 60 and avoids any tendency which the moving liquid might have to flow past the valve member. Another advantage is that the liquid in the tube 35 presses against the valve and tends to supplement the action of the spring 44 in opening the valve. Still another advantage of my present valve construction is the ease with which the parts can be removed for inspection or repair. Unscrewing and removing the plug 27 releases all of the parts of the valve and they may be drawn out of the casing 26 after the plug 27 is removed.

As is well known, flow of liquid through a valve tends to disintegrate the column or mass of liquid. As it is desirable to expel the fire extinguishing liquid in a solid stream, thereby enabling the stream to be thrown considerable distances, I provide a comparatively long tubular passage for the liquid after it has passed through the valve, thereby giving the liquid a chance to con-

solidate. I have also found solidity of the ejected stream is preserved by having the liquid traverse a straight tube whose axis coincides with that of the stream, for some distance before it issues from the nozzle, say an inch or thereabout, where the diameter of the stream is about one-sixteenth of an inch. For these reasons I carry the liquid from the inner end of the valve casing 26 by means of the comparatively long tube 61, and provide a straight section of this tube to connect to the nozzle, the axis of this part of the tube and that of the tube coinciding, in preference to taking a short cut from the valve casing to the nozzle.

While I have shown and described what I at present regard as the preferred embodiment of my invention, it is not to be understood that I consider my invention limited to this embodiment. Various modifications are possible without departing from the spirit of my invention or exceeding the scope of my claims. What I claim as my invention is as follows:

1. In a fire extinguisher, a liquid container, a discharge nozzle therefor, a valve casing having an inlet for liquid from the container and an outlet connected to said nozzle, means for forcing a liquid from the container to the said valve casing, a valve adapted to close said inlet, a spring adapted to open said valve, a second spring tending to resist the action of the first spring and to urge the valve toward closed position but normally under insufficient tension to overcome the action of said first spring, and manually operable means effective only during periods of non-operation of the extinguisher for increasing the tension of the second spring to cause said second spring to close said valve.

2. In a fire extinguisher, a liquid container, a nozzle therefor, a valve casing having an inlet for liquid from the container and an outlet connected to said nozzle, pumping means for forcing liquid from the container to said valve casing, a valve adapted to close said inlet, a spring adapted to open said valve, a second spring adapted to have tension sufficient to overpower the first and close the valve, and a manually operable member on the outside of the container rotatably mounted and adapted by rotary motion to impart to said second spring sufficient tension to overpower the first spring and close the valve, said manually operable member being associated with said pumping means to effect actuation thereof without effecting closing movement of said valve in all operative positions of pumping movement of said member.

3. In a fire extinguisher, a liquid container having a nozzle, a valve casing in the container, having an inlet for liquid from the container and an outlet connected to said

nozzle, a valve adapted to close said inlet, a spring constantly tending to open said valve, a second spring adapted to have tension sufficient to overpower the first and close the valve, an element extending to the exterior of the casing, and a manually operable member on the outside of the casing adapted by rotary motion to impart motion to said element whereby said second spring is put under tension and the valve closed.

4. In a fire extinguisher, a liquid container having a nozzle, a valve casing therein having an inlet for liquid from the container and an outlet connected to the nozzle, a valve in the casing adapted to cover said inlet, a spring tending constantly to lift the valve from the inlet, a second spring, a plunger extending from the interior of the casing to the exterior of the container, and a manually operable member on the outside of the container adapted to rotate with reference thereto, said member carrying a cam adapted to engage the plunger and push the plunger in as said member is rotated, the inner end of the plunger bearing upon said second spring, whereby as the plunger is pushed in the spring is put under tension sufficient to overpower the first spring and close the valve.

5. In a fire extinguisher, a liquid container having a nozzle, a valve casing therein having an inlet for liquid from the container and an outlet connected to the nozzle, a valve in the casing adapted to cover said inlet, a spring tending constantly to lift the valve from the inlet, a second spring, a plunger extending from the interior of the casing to the exterior of the container, and a manually operable member on the outside of the container adapted to rotate with reference thereto, said member carrying a cam adapted to engage the plunger and push the plunger in as said member is rotated, the inner end of the plunger bearing upon said second spring, whereby as the plunger is pushed in the spring is put under tension sufficient to overpower the first spring and close the valve, said cam having a depression on its highest part, into which the end of the plunger drops, forming a latch which holds said member from rotating with sufficient firmness to prevent its accidental rotation, the cam moving the plunger far enough to permit this slight recession while retaining sufficient tension in the spring to keep the valve closed.

6. In a fire extinguisher, a liquid container having a nozzle, a valve casing therein having an inlet for liquid from the container and an outlet connected to the nozzle, a valve in the casing adapted to cover said inlet, a spring tending constantly to lift the valve from the inlet, a second spring, a plunger extending from the interior of the

casing to the exterior of the container, a pump in the container having a reciprocable piston rod which extends to the outside of the container near said plunger, a handle for reciprocating said piston rod, said handle being revoluble as well as reciprocable and provided with a bayonet catch to lock the handle in its innermost position, a cam carried by the handle, adapted as the handle is rotated, after the bayonet catch is locked, to engage, and cam the plunger inward, the inner end of the plunger bearing upon said second spring and putting the spring in tension as it is cammed in, thus closing the valve by rotary motion of the handle.

7. In a fire extinguisher, a liquid container, a nozzle therefor, a passage to carry liquid from said container to said nozzle, and mechanism for preventing the flow of liquid through said passage, comprising a valve, a spring tending constantly to open said valve, a second spring, a manually operable member on the outside of the container, and means associated with said manually operable member and said second spring adapted upon rotation of said manually operable member to impart tension to the second spring sufficient to overpower the first spring and close said valve.

8. In a fire extinguisher, a liquid container having a top, a cylindrical valve casing in said container, one end of which is secured to said top, a plug removable from the outside of the casing, closing the end of said casing, said plug carrying a longitudinally slideable plunger, a port in the inner end of the casing, a piston-like valve member in said casing adapted to close said port, a spring confined between the inner end of the casing and said member constantly tending to press the valve member away from said port and leave the port open, a second spring between said valve member and the inner end of said plunger, and means on the exterior of the casing for pressing the plunger inward, thereby compressing the second spring so as to give it sufficient tension to overcome the first spring and press the valve member over said port.

9. In a fire extinguisher, a liquid container having a top, a valve casing in the container, one end of which is secured to said top, a plug removable from the outside whereby said end of the casing is closed, a longitudinally movable plunger carried by said plug, a port in the opposite end of said casing having a valve seat, a valve member in said casing, adapted to occupy said seat and close the port, or occupy a seat formed on the inner end of said plug and thus seal the casing, a spring tending constantly to move the valve member to the latter seat, a second spring, and manually operable means on the exterior of the container adapted to press the plunger inward and on the second

spring, thereby compressing said spring and endowing it with enough tension to overpower the first mentioned spring and seat the valve member on the port seat.

5 10. In a fire extinguisher, a liquid container having a top, a cylindrical valve casing in the container, one end of which is secured to said top, a plug whereby, said end of the casing is closed, a longitudinally movable plunger mounted in said plug, a tube secured in the opposite end of the casing and extending some distance toward said plug, the end of the tube being adapted to form a seat for a valve, a cup-shape valve member adapted to slide in the casing between said valve seat and a seat formed upon the end of said plug, said tube extending into the cup, a spring surrounding said tube and confined between the bottom of the 15 cup and the end of the casing, whereby the valve member is pressed against the seat on the end of the plug, thus sealing the casing, a second spring, and manually operable means on the outside of the container whereby to press the plunger inward, the plunger bearing upon said second spring and compressing it, thereby giving said spring sufficient tension to overpower the first spring and seat the valve on the end of said tube.

20 11. In a fire extinguisher, a liquid container having a top, a cylindrical valve casing in the container, one end of which is secured to said top, a plug whereby said end of the casing is closed, a longitudinally movable plunger mounted in said plug, said plunger being shorter than the bore of the plug, a tube secured in the opposite end of the casing and extending some distance toward said plug, the end of the tube being 25 adapted to form a seat for a valve, a cup-shape valve member adapted to slide in the casing between said valve seat and a seat formed upon the end of said plug, said tube extending into the cup, a spring surrounding said tube and confined between the bottom of the cup and the end of the casing, whereby the valve member is pressed against said seat on the end of the plug, thus closing the inner end of the plug, a second spring, 30 said spring being housed by the portion of the bore of the plug not occupied by the plunger, and manually operable means on the outside of the container whereby to press the plunger inward, the plunger bearing on the end of the second spring and by compressing the spring giving it sufficient tension to overpower the first spring and press the valve against the end of said tube.

35 12. In a fire extinguisher, a liquid container having a top, a valve casing in the container, one end of which is secured to said top, a plug whereby said end of the casing is closed, a longitudinal bore in said plug, the inner portion being of larger diameter than the outer portion, a plunger in said smaller

bore having a head which occupies a small portion of the larger bore, a port in the opposite end of the casing having a valve seat, a valve member adapted to move in the casing and occupy said seat or occupy a valve seat 70 formed on the end of said plug, a spring constantly tending to move the valve and press it to the latter seat, a spring housed in said bore in the plug, a sealing disk being interposed between the end of said spring and the head of the plunger, the length of said spring when free from tension being slightly less than the space afforded by the bore, so that the valve member can lie against the end of the plug without opposition from this spring, and means for pressing the plunger inward to compress this spring and give it sufficient tension to overpower the first spring and press the valve against said port.

75 13. A portable fire extinguisher comprising an elongate liquid container having a fixed nozzle at one end with a bore extending radially with reference to the longitudinal axis of the container, a fixed tube, one end of which is connected to said nozzle, the other or open end being situated at the far end of the container on a line radiating from said axis at an angle of from ninety to one hundred and twenty degrees from the line on which the bore of the nozzle lies, and a piston 80 pump in the container, lying longitudinally thereof in substantially the same radial plane that the open end of said tube lies in, the construction being such that when the container is held in a reclining position with the nozzle end somewhat elevated and the nozzle directed away from the operator, the open end of said tube will be in approximately 85 the lowermost part of the container.

90 14. A portable fire extinguisher comprising an elongate liquid container having a fixed nozzle at one end with a bore extending radially with reference to the longitudinal axis of the container, and a fixed tube, one end of which is connected to said nozzle, the other or open end being situated at the far end of the container on a line radiating from said axis at an angle of from approximately 90° to 120° from the radial plane in which the nozzle lies, the construction being 95 such that when the container is held in a reclining position with the nozzle end somewhat elevated and the nozzle directed away from the operator, the open end of said tube will be in approximately the lowermost part 100 of the container.

110 15. A portable fire extinguisher comprising an elongate liquid container having a fixed nozzle at one end with a bore extending radially with reference to the longitudinal axis of the container, and a fixed tube, one end of which is connected to said nozzle, the other or open end being situated at the far end of the container on a line radiating from 115 said axis at such an angle that with the con- 120

tainer held in a reclining position with the nozzle end somewhat elevated the open end of said tube will be in approximately the lowermost part of the container when the 5 nozzle is directed approximately straight away from the operator.

16. In a fire extinguisher, a liquid container, a pump therein having a piston rod extending to the exterior thereof, a discharge 10 nozzle, valve mechanism in the container having a member extending to the exterior, which member upon being pushed inward closes the valve and prevents discharge of liquid through said nozzle, means for locking the piston rod to the container to prevent longitudinal movement while permitting rotary movement, and a cam carried by the piston rod whereby to press said member inward and close the valve by rotary movement of the rod.

17. In a fire extinguisher, a liquid container, a pump therein having a piston rod extending to the exterior thereof, a discharge nozzle, valve mechanism in the container 25 having a member extending to the exterior, which member upon being pushed inward closes the valve and prevents discharge of liquid through said nozzle, said member being connected to the valve mechanism by a compression spring, means for locking the piston rod to the container to prevent longitudinal movement while permitting rotary movement by the rod, and a cam carried by the piston rod whereby to press said member inward far enough to endow said spring with sufficient tension to close the valve.

18. In a fire extinguisher, a liquid container, a fluid pump for forcing liquid from said container, a nozzle therefor, a valve 40 casing having an inlet for liquid from the container and an outlet connected to said nozzle, a valve adapted to close said inlet, a spring constantly tending to open said valve, a second spring adapted to be put under tension sufficient to overcome the first and close the valve; an element extending to the exterior of the extinguisher and operatively associated with said second spring to alter the tension thereof upon movement of 45 said element, and a member on the outside of the casing manually operable and adapted to impart motion to said element whereby said second spring is put under tension and the valve closed.

55 19. In a fire extinguisher, a liquid container having a nozzle arranged transversely to the container and projecting from the surface thereof at the most only a short distance, a tube connecting the interior of the 60 container to the nozzle, a pump within the container for forcing the liquid within the container through the tube to the nozzle and provided with a handle reciprocable longitudinally of said container, that portion of 65 the tube adjacent the nozzle and in the con-

tainer being in axial alignment with the bore of the nozzle for a substantial distance to effect the discharge of a solid stream from said extinguisher, and a manually operable shut-off valve located in said tube in advance of the axially aligned portion thereof for controlling the flow of the liquid through said tube to said nozzle.

20. In a fire extinguisher, a liquid container having a nozzle arranged transversely to the container, a tube connecting the interior of the container to the nozzle, a pump extending within said container for forcing the liquid within the container through the tube to the nozzle, and a valve for controlling flow of the liquid through said tube to the nozzle, that portion of the tube adjacent the nozzle being in axial alignment with the bore of the nozzle for a distance of approximately one inch with a nozzle having a bore of approximately one-sixteenth of an inch to effect the discharge of a solid stream from said extinguisher.

21. In a fire extinguisher, a liquid container having a nozzle arranged transversely to the container, and a valve for shutting off the flow of liquid through said nozzle, the valve being connected to the nozzle by a curved tube positioned within said container, the part of the tube which connects to the nozzle being in axial alignment with the bore of the nozzle for a distance of approximately one inch with a nozzle having a bore of approximately one-sixteenth of an inch to effect the discharge of a solid stream from said extinguisher.

22. A portable fire extinguisher comprising an elongate liquid container having a fixed nozzle with a bore extending radially with reference to the longitudinal axis of the container, a fixed tube, one end of which is connected to said nozzle, the other open end being situated at the end of the container which is lowermost when the extinguisher is held inclined in normal operating position, the said open end of said tube being located on a line radiating from the longitudinal axis of the container at such an angle with respect to the radial plane in which the nozzle lies that when said extinguisher is held in normal operating position with the nozzle directed substantially straight away from the operator, the said open end of said tube will be in approximately the lower most part of the container.

23. A portable fire extinguisher comprising an elongate liquid container adapted to be held in an inclined normal operating position, a pump for forcing liquid from said container extending longitudinally within said container and positioned eccentrically with respect to the longitudinal axis of said container, a liquid intake opening adjacent the end of the container which is normally held lowermost and adjacent the portion of

the side of the container at which said pump is positioned and a discharge nozzle having a bore extending radially with respect to the longitudinal axis of said extinguisher and positioned at such an angle with reference to the radial plane in which said pump lies that when said extinguisher is held in normal operating position with said nozzle directed substantially straight away from the operator, the said pump and the said liquid intake will be adjacent the portion of the side of said container which is lower-most.
